UNITED STATES PATENT OFFICE.

JOHN A. WHALEY, OF NEW YORK, N. Y.

DESIGN FOR A LAMP-SHADE.

No. 39,772.

Specification for Design.

Patented Jan. 19, 1909.

Application filed February 27, 1908. Serial No. 418,155. Term of patent 3½ years.

To all whom it may concern:

Be it known that I, JOHN A. WHALEY, a citizen of the United States, residing at No. 258 West Twenty-third street, city, county, and State of New York, have invented a new, original, and ornamental Design for a Lamp-Shade, of which the following is a specification, reference being made to the accompanying drawing, in which the lamp-shade is illustrated in perspective.

What I claim is—
The ornamental design for a lamp-shade as shown.

JOHN A. WHALEY.
